Primary Examiner — Kevin K Rudzinski(74) Attorney, Agent, or Firm — Banner & Witcoff, Ltd.(57) CLAIM

The ornamental design for a waistband, as shown and described.

DESCRIPTION

FIG. 1 is a front view of a waistband showing my new design;

FIG. 2 is a rear view thereof;

FIG. 3 is a top view thereof; and,

FIG. 4 is an enlarged view of area 4 labeled in FIG. 1 thereof.

The broken lines immediately adjacent to the photographic area define the bounds of the claimed design and form no part thereof.

1 Claim, 4 Drawing Sheets(56)
